PEDESTAL AND WEAR PLATE FOR RAILWAY CARS

Filed March 22, 1922

Edward Posson

by Sheridan Jones, ³ ₂ Sheridan, ³ ₂ 1923.

UNITED STATES PATENT OFFICE.

EDWARD POSSON, OF CHICAGO, ILLINOIS.

PEDESTAL AND WEAR PLATE FOR RAILWAY CARS.

Application filed March 22, 1922. Serial No. 545,707.

To all whom it may concern:

Be it known that I, EDWARD POSSON, a citizen of the United States, residing at Chicago, in the county of Cook and State of Illinois, have invented certain new and useful Improvements in Pedestals and Wear Plates for Railway Cars, of which the following is a specification.

This invention relates to improvements in pedestals and wear plates for railway cars, and has for its object to provide a pedestal which has means to enable the quick and ready attachment of a wear plate thereto between the pedestal and the journal box. 15 Another object consists in the provision of a new article of manufacture comprising a wear plate.

These and other objects will be more fully outlined and described in the following 20 specification and shown in the accompanying drawings, in which—

Figure 1 is a side elevation of a pedestal;

Fig. 2 is a vertical section thereof, taken on the line 2—2 of Fig. 1;

Fig. 3 is a horizontal section, taken on the line 3—3 of Fig. 2;

Fig. 4 is a perspective view of one jaw of the pedestal, showing the wear plates attached thereto; and

Fig. 5 is a plan view of the blank from which the wear plate is constructed.

Like numerals refer to like elements throughout the drawings, in which—

10 indicates generally a pedestal having 35 depending spaced jaws 10^a provided with spaced vertical ribs 10^b constructed to engage a journal box and ride in grooves therein, as is well known to those skilled in the

art. At their upper and lower ends the ribs 10^b are undercut, as indicated by the numerals 10^c and 10^d, designating the upper and lower undercuts, respectively. Wear plates 12, of steel or the like, are provided, having projecting tabs or tongues 12^a at the top and bottom thereof, and side flanges 12^b. The 45 sides of the wear plates may be bent before or after attachment to the ribs. The tongues 12^a are bent around the undercut extremities of the ribs 10^b at the top and bottom, as shown, for example, in Fig. 1, and serve to 50 hold the wear plates securely on the ribs, thereby receiving the wear from frictional contact with the journal box or wear plates carried by the journal boxes.

It will be apparent that with this construction of pedestal and wear plate attachment or replacement of the wear plates to the pedestals requires the expenditure of little time and labor, and results in the secure mounting of the wear plates.

It will be understood that I do not wish to be restricted to the form of my invention shown and described herein, except as defined in the appended claim.

I claim:—

In combination, a pedestal having depending jaws, said jaws being provided with ribs, said ribs being undercut at their upper and lower extremities, and wear plates mounted on said ribs and having portions 70 bent over and engaging the undercut extremities of said ribs.

In testimony whereof, I have subscribed my name.

EDWARD POSSON.
